UNITED STATES PATENT OFFICE.

JOHN WISNIEWSKI AND STANISLAU WISNIEWSKI, OF POUGHKEEPSIE, NEW YORK.

RAILROAD-CAR.

1,262,894.

Specification of Letters Patent. Patented Apr. 16, 1918.

Application filed January 29, 1918. Serial No. 214,299.

To all whom it may concern:

Be it known that we, JOHN WISNIEWSKI, a citizen of the United States, resident of Poughkeepsie, county of Dutchess, and State 5 of New York, and STANISLAU WISNIEWSKI, a citizen of the United States, resident of Poughkeepsie, county of Dutchess, State of New York, have invented certain new and useful Improvements in Railroad-Cars, of 10 which the following is a specification.

This invention relates to improvements in rail road cars and the principal object of the invention is to provide a car having removable or foldable bunks which may be 15 dismounted and carried in the car when not in use so that the car may be used for the transmittal of freight and the like.

Another object of the invention resides in the provision of bunks as above described 20 which may be readily set up for use with a minimum amount of labor.

As a further object the invention contemplates the use of novel supporting means for the bunks which are adapted to be placed 25 in pockets in the sides of the car which are formed by the uprights and braces of the car body.

With these and other objects in view the invention consists in the novel construction, 30 combination and arrangement of parts as will be fully set forth in the following specification, claimed and illustrated in the accompanying drawings, in which;

Figure 1, is a transverse vertical sectional view through a car constructed in accordance with this invention.

Fig. 2, is a vertical sectional view through Fig. 1 taken on line 2—2 thereof,

Fig. 3, is a horizontal sectional view taken 40 on line 3—3 of Fig. 2,

Fig. 4, is an enlarged detail perspective view of one of the supporting hooks illustrating the hanger bar therefor in detail.

Fig. 5, is a view similar to Fig. 1, showing the bunks in folded position, and

Fig. 6 is a fragmentary detail view showing the means by which the legs are held in position in the car floor.

Referring to the drawings by characters 50 of reference, the numeral 1, designates as an entirety a car which comprises a bottom 2, provided with the side walls 3, which are supported on suitable uprights 4. These uprights are braced by the braces 5 which 55 form pockets 6, the use of which will appear as the description proceeds. The usual

roof covers the entire car as clearly shown on the drawings.

Attached to the uprights 4, are spaced horizontally extending hanger bars 7, which 60 are notched around the uprights as illustrated in Fig. 3, so as to present flat faces to the uprights and thereby insure the firm positioning of said bars against the said uprights.

The bunks are designated by the numerals 8, and each comprises a body portion 9, having attached thereto transverse straps 10, the rear ends of which are bent upwardly as at 11, and provided with eyes 12 for the reception of the supporting hooks 13. As shown 70 the inner or rear ends of the bunks are supported on the hooks which are in turn supported on the hanger bars 7, while the outer ends of the bunks are supported on the legs 14. An opening 15 is formed near the outer corners of the lower bunk 8, and is adapted to receive a locking pin 16, by means of which the legs are prevented 75 from falling outwardly. In order to keep 80 the lower end of each of the lower legs from becoming displaced when the device is in use the floor or bottom of the car is provided with openings 17, for the reception of lugs 18 formed on plates 19, which are attached 85 to the lower ends of the said lower legs as clearly illustrated in the drawings.

In order to further support the outer edges of the upper bunks the hooks 20 are carried by the end walls of the car and these 90 hooks enter eyes 21 which are attached to the bunks in any suitable manner.

A retaining bar 22 is attached to the uprights 4, between the upper and lower hanger bars and this bar is provided with a 95 ledge or flange 23, the use of which will be more fully hereinafter described.

In operation it will be understood that the hooks 13 are first placed on the bars 7 and the same are then passed through the 100 eyes 12 so that the rear edge of the bunks will be held in position. The lower legs 14 are then placed beneath the lower bunk with the lugs 18 entering their respective openings 17 and in this way it will be seen 105 that the lower bunk will be supported in operative position. The legs of the upper bunk are then placed beneath the outer edge thereof and on the lower bunk after which the pins 16 are passed through the openings 110 15 and it will be evident that the legs will thus be prevented from being displaced.

When it is desired to clear the interior of the car for use as a freight car or the like it will be understood that the bunks are removed and placed on the bar 22 as shown in Fig. 5 and the legs and hooks are placed in the pockets 6 as illustrated in Fig. 2. In this way it will be seen that the entire interior of the car may be used for storage and interference of the bunks with the contents will be avoided. In this way it will also be apparent that in case of emergency the bunks being in the car, they may be easily put into operation and the necessity of building makeshift bunks will be avoided.

While in the foregoing there has been shown and described the preferred embodiment of this invention it will be understood that certain minor changes in the construction, combination and arrangement of parts may be resorted to without departing from the spirit and scope of the invention as claimed.

What is claimed is:—

1. In a car, hanger bars, removable bunks, hooks for connecting the bunks to the hanger bars, and holding the rear ends of the bunks in spaced relation and legs for holding the forward ends of the bunks in spaced relation, said legs engaging in openings formed in the floor of the car.

2. In a car, hanger bars, removable bunks, hooks for connecting the rear ends of the bunks to the hanger bars and supporting them in spaced relation, legs for holding the forward ends of the bunks in spaced relation and means for holding the legs against accidental outward movement.

3. In a car, a bottom, side walls, uprights supporting the side walls, braces for the uprights, said uprights and braces forming pockets, hanger bars attached to the uprights, hooks removably secured to the hanger bars, bunks, eyes carried by the bunks and adapted to receive the hooks to support the rear ends of the bunks in spaced relation, legs for supporting the forward ends of the bunks in spaced relation, lugs on the lower legs for entering the floor of the car to prevent said legs from being displaced, and pins passing through the bunks for holding the upper ends of the legs in position.

In testimony whereof we have affixed our signatures.

JOHN WISNIEWSKI.

STANISLAU WISNIEWSKI.
